ELECTRIC HAIR BRUSH

Hans Carl Haluss, New Westminster, British Columbia, Canada

Application February 7, 1938, Serial No. 189,217

7 Claims. (Cl. 15—21)

This invention relates to an improved electric hair brush particularly for human use.

An object of the present invention is the provision of an electric hair brush adapted to remove dandruff and foreign matter from the hair and scalp.

Another object is the provision of an electric hair brush capable of removing excess oil from the hair and scalp without removing all the natural oil therefrom.

Another object is the provision of an electric hair brush adapted to massage the scalp.

A further object is the provision of a comb, in combination with an electric hair brush, adapted not only to comb the hair but to form partings or furrows therein to permit the bristles of the brush to reach the scalp to remove dandruff and dirt therefrom.

A further object is the provision of a comb, in combination with an electric hair brush, designed to massage the scalp by transferring vibrations thereto without hurting the head and without damaging the scalp or hair.

Yet another object is the provision of an improved rotary brush and comb combined with means for massaging the scalp.

A still further object is the provision of a device of the character described, of durable and compact construction and which may be very easily handled.

It is well known that brushing cleans the hair and that massaging the scalp by vibrations enlivens it. The present invention combines these operations so that one treatment cleans both the hair and the scalp. This has never been done before.

The combination of a comb and a rotary brush has been used for cleaning short-haired animals but the known devices cannot be used satisfactorily upon human beings or long-haired animals. The reason for this is that the combs of these devices merely stir up the hair in order to loosen the dirt to be removed by the rotary brush. These grooming devices would not clean the comparatively long hair of a human being since the brush cannot reach to the scalp. The comb merely stirs up the hair but does not part it to a sufficient extent as to permit the brush to get right to the bottom thereof, with the result that only the outer surface of the hair would be cleaned. The present invention overcomes this difficulty by providing, in combination with a rotary brush, a comb adapted to reach right down to the scalp and to form furrows in the hair which are long enough to permit the bristles of the brush to

contact the scalp. The furrows are of such a shape, in cross section, that the brush not only cleans the scalp but it cleans the hair right from the roots to the ends thereof. The comb of this invention is such that it maintains the brush at a proper distance from the head and acts as a guide for the whole device. The combs of the known devices could not be used for this purpose since they would certainly cut or injure the scalp.

The comb of the present invention is also used to transmit vibrations to the scalp in order to massage it as the hair is combed and brushed. Here again, the combs of the known devices could not act in this capacity since they are relatively sharp and, therefore, would hurt the scalp.

At the present time, the common method of cleaning the scalp and hair of human beings is by shampooing. This takes considerable time and is bad for the hair since it completely removes the natural oils from both the scalp and the hair. This makes the hair dull, dry and brittle so that it appears lifeless and breaks easily. In contrast to this, the present invention provides a hair brush by means of which the hair and scalp may be quickly and completely cleaned without removing the natural oils although means is provided for removing the excess oils.

This invention consists essentially of an electric hair-brush having a rotary brush mounted therein, means for rotating said brush, a comb mounted beneath the brush with means for forming furrows in the hair to permit the bristles of the brush to reach the scalp, and a casing associated with the brush adapted to rotate in an elliptical path to create vibrations which are transmitted to the scalp by the comb, as more fully described in the following specification and illustrated in the accompanying drawings in which

Figure 1 is a longitudinal sectional view of the electrical hair brush, taken along the line 1—1 of Fig. 2, with the bristles of the brush in a position to contact the scalp.

Figure 2 is a plan view of the electrical brush with the cover removed and certain parts broken away to show the interior thereof.

Figure 3 is a vertical section taken on the line 3—3 of Fig. 1.

Figure 4 is a perspective view of the vibratory casing.

Figures 5 to 8 inclusive, are fragmentary views similar to Fig. 1, which, along with Fig. 1, show the movement of the rotary brush through one complete revolution or cycle.

Figure 9 is a bottom plan view of the comb of the electric hair brush,

Figure 10 is a sectional view of the comb taken along the line 10—10 of Fig. 9,

5 Figure 11 is a vertical sectional view of the casing shown in Fig. 4, and

Figure 12 is a perspective view of the electric hair brush.

Referring more particularly to the drawings,

10 A is the electric hair brush in which 10 is a base plate having an enlarged opening 11 therein which is preferably closer to the rearward end 12 than to the forward end 13 of said base plate. A brush compartment 14 is formed over the 15 opening 11 of the base plate 10 by a shield 15 and side plates 16 and 17, which side plates are spaced inwardly from the sides of the base plate. The shield 15 extends upwardly and rearwardly in a curve from the forward end of the opening 20 11 and terminates in a short flap 18 spaced above and lying parallel to the base plate while the rearward ends of the side plates 16 and 17 diverge outwardly as extensions 20 and 21, respectively. The flap 18, the extensions 20 25 and 21 and the base plate 10 form a short passage 22 at the rearward end of the compartment 14, into which a brush 23 removably fits, said brush having a plurality of bristle tufts 24 extending into the compartment and a handle 25 30 extending outwardly therefrom. A cover or casing 26 removably fits over the base plate 10 enclosing the operating compartment 14 and forming a motor compartment 27 in which a small electric motor 28 is mounted. A switch 35 30 mounted in the cover 26, is connected by wires 31 to the motor and a socket 32 also mounted in the cover 26 beside the switch 30, is adapted to receive one end of a lead cord 33, the other end of which may be connected to any 40 suitable electrical outlet.

A main shaft 34 journalled in the side plates 16 and 17, extends laterally of the compartment 14 above the opening 11 in the base plate 10. This shaft is circular in cross section at its ends 45 while the central portion thereof is rectangular in cross section, as at 35. Two diametrically opposed sets of bristle tufts 36 and 37 extend outwardly from the shaft 34, with the outer end of each tuft substantially V-shaped, as clearly shown in Fig. 3. One end of the shaft 34 extends through the side plate 16 and has a pulley 38 mounted thereon, which pulley is connected by a suitable belt 40 to a pulley 41 mounted on the drive shaft 42 of the motor 28. The shaft 34 and the sets of bristle tufts 36 and 37 form a brush 43 adapted to be rotated by the motor 28. When the brush 43 rotates, the outer ends 55 of the bristle tufts thereof move along a circular path, indicated by the circle 44 in Fig. 5.

60 A pair of discs 45 and 46 are mounted exactly opposite each other on the inner surfaces of the side plates 16 and 17, respectively. These discs are mounted eccentrically in relation to the shaft 34 so that the ends of the shaft extend through 65 said discs at points adjacent the peripheries and the bottoms thereof.

A casing 47, see Fig. 4, is adapted to be mounted in the compartment 14. This casing may take the form of a cylinder or a cylindroid or it may be shaped as shown. In the drawings, 70 two sets of diametrically opposed, substantially semi-cylindrical structures 48 and 50 are combined to form the casing 47. Suitably shaped blocks 51 are fitted in the semi-cylindrical structures 48 with their inner surfaces 52 spaced apart

and parallel to each other. The inner surfaces 52 of the blocks 51 and the structures 50 form an elongated slot or guideway 53 extending longitudinally and centrally of the casing 47, which slot or guideway has parallel sides and semi-circular ends. Each block 51 is formed with a slot 54 extending outwardly from the guideway 53 and through the casing 47, said slot gradually widening towards the guideway, as at 55. The slots 54 do not extend the full length of the 10 casing 47 but terminate short of each end of the casing. Guide or bearing passages 56 extend through each block 51 and the casing between each end of the slots 54 and the adjacent ends of said casing.

15 The casing 47 mounted in the compartment 14, surrounds the main shaft 34 with the eccentric discs 45 and 46 extending into the opposite ends of the guideway 53 and the opposing sets of bristle tufts 36 and 37 extending through the 20 slots 54. The main shaft 34 is provided adjacent the ends of the rectangular section thereof with two sets of diametrically opposed, radial rods 57 which extend outward into the guide or bearing passages 56. The rods 57 cause the 25 casing 47 to rotate with the shaft 34 and, at the same time, permit a reciprocating motion of the casing.

A comb 58 secured to the bottom of the base plate 10, is provided centrally thereof with an 30 enlarged opening 60 registering with the opening 11 of said base plate. Recesses 61 having curved bottoms 62, are formed in the comb 58 at each side of the opening 60. The comb is formed with a plurality of elongated, substantially 35 V-shaped teeth 63 at its forward end and at each side thereof with substantially V-shaped runners or teeth 64 which extend the full length of the comb. The teeth 63 extend from the forward end of the comb rearwardly to a point 40 overlapping the opening 60 while the forward ends of said teeth and the teeth 64 preferably extend outwardly from the comb and taper downwardly to a point, as at 65. While the comb 58 has been shown as an independent unit it 45 will be understood that the teeth 63 and 64 could be mounted directly on the bottom of the base plate 10.

In use, the electric hair brush is drawn over the scalp in the direction of the arrow 66 (Fig. 50 1), and the brush rotates in the direction of the arrow 67 (also Fig. 1). The rotary brush 43 rotates in a circle while a rotary and reciprocatory motion are simultaneously imparted to the casing 47 so that the outer surfaces of the 55 structures 48 move along a substantially elliptical path illustrated by the ellipse 68 in Fig. 5. This elliptical movement is due to the fact that the discs 45 and 46 are mounted eccentrically in relation to the shaft 34 which results in the 60 casing 47 moving back and forth over the discs within the limits of the guideway 53, as said casing is rotated about the discs. In other words, the centre of rotation of the casing is constantly changing as distinct from the centre of 65 rotation of the rotary brush which remains stationary. There are times when the casing and the rotary brush are concentric but the casing rotates eccentrically to said brush during the greater part of the time.

70 A complete cycle of the rotary brush 43 and the casing 47 is illustrated in Figs. 1 and 5 to 8, inclusive. The bristle tufts 36 and 37 of the rotary brush are of such length that when the brush is in a vertical position, as in Fig. 1, the 75

outer ends of the lowermost set of bristle tufts lie in the same plane as the lower edges of the teeth 63 and, consequently, contact the scalp.

of the casing so that the hair cannot become entangled or caught between the ends of the casing and the side plates 16 and 17.

In the above, the casing 47 has been described as a brush cleaner. However, this casing has another purpose and that is it acts as a vibrator. This casing rotates through an elliptical path with the result that it creates a vibration through the eccentric discs 45 and 46, the side plates 16 and 17 and the base 10, which vibration is transmitted to the scalp by the teeth 63 and 64 of the comb. The teeth 63 are fairly long while the teeth 64 are quite a length with the result that the vibrations are transmitted simultaneously to a relatively large area of the scalp. In this way, the scalp is massaged as well as being brushed and cleaned, when the hair brush A is drawn over the scalp. The length of the teeth 63 and 64 prevent said teeth from digging into the scalp as a result of the vibration. 5 10 15 20

From the above, it will be seen that the teeth of the comb 58 divide the hair into furrows to permit the bristle tufts of the rotary brush to reach and clean the scalp and clean the hair right down to the roots; the casing 47 prevents the hair from being drawn into the compartment 14 and at the same time, it removes the coarse dirt, dandruff and loose hair from said tufts, which dirt, dandruff and hair is deposited upon the bristle tufts of the brush 23 which also removes the finer dirt and oil from the rotary brush; and the casing 47 by rotating in an ellipse, creates vibrations which are transmitted to the scalp by the comb, the teeth of which are of such a length as to transmit the vibrations to a relatively large area of the scalp without injuring it.

10. This electric hair brush which is small, durable and easily handled, cleans all the dirt and loose dandruff from the scalp and hair, removes loose hair and excess oil without removing all the natural oil which is essential to the welfare of the hair, and massages the scalp to stimulate the growth of the hair. 40

Various modifications may be made in this invention without departing from the spirit thereof or the scope of the claims, and therefore the exact forms shown are to be taken as illustrative only and not in a limiting sense, and it is desired that only such limitations shall be placed thereon as are disclosed in the prior art or are set forth in the accompanying claims. 45

What I claim as my invention is:

1. An electric hair brush comprising a casing having an opening in the bottom thereof, a rotary brush mounted in the casing over said opening, said brush having a plurality of bristle tufts adapted to project through the opening, means in the casing for rotating the brush, and a plurality of longitudinally extending elongated teeth mounted on the bottom of the casing immediately in advance of and in line with the bristles projecting through the opening therein, said teeth being adapted to form furrows in the hair to permit the bristle tufts to reach the scalp during the rotation of the rotary brush.

2. An electric hair brush comprising a casing having an opening in the bottom thereof, a rotary brush mounted in the casing over said opening, said brush having a plurality of bristle tufts adapted to project through the opening, means in the casing for rotating the brush, and a plurality of longitudinally extending, elongated teeth of V-shape cross section mounted on the bottom of the casing immediately in advance of and in

- line with the bristles projecting through the opening therein and extending beneath part of said opening, said teeth being adapted to form furrows in the hair and to retain the furrows open 5 to permit the bristle tufts to reach the scalp during the rotation of the rotary brush.
3. An electric hair brush comprising a casing having an opening in the bottom thereof, a rotary brush mounted in the casing over said opening, 10 said brush having a plurality of bristle tufts adapted to project through the opening, each bristle tuft being V-shaped at its outer end, means in the casing for rotating the brush, and a plurality of longitudinally extending, elongated teeth 15 of V-shape cross section mounted on the bottom of the casing immediately in advance of and in line with the bristles projecting through the opening therein, the rearward ends of the teeth overlapping the opening and the forward ends thereof extending away from said brush and 20 downwardly to a point, said teeth being adapted to form furrows in the hair and to retain the furrows open to permit the V-shaped ends of the bristle tufts to reach the scalp during the rotation 25 of the rotary brush.
4. An electric hair brush comprising a casing having an opening in the bottom thereof, a compartment formed in the casing over said opening, a brush removably mounted in the casing 30 having bristle tufts extending into the compartment, a rotary brush mounted in the compartment, said brush having a plurality of bristle tufts adapted to pass through the bristle tufts of the first brush and to project through the 35 opening as the rotary brush rotates, means in the casing for rotating the latter brush, and a plurality of longitudinally extending, elongated teeth mounted on the bottom of the casing immediately in advance of and in line with the 40 bristles projecting through the opening therein, said teeth being adapted to form furrows in the hair to permit the bristle tufts of the rotary brush to reach the scalp.
5. An electric hair brush comprising a casing 45 having an opening in the bottom thereof, a compartment formed in the casing over said opening, a brush removably mounted in the casing having bristle tufts extending into the compartment, a rotary brush mounted in the compartment, said 50 brush having two diametrically opposed sets of bristle tufts adapted to pass through the bristle tufts of the first brush and to project through the opening as the rotary brush rotates, means in the casing for rotating the latter brush, and a plurality of longitudinally extending, elongated teeth mounted on the bottom of the casing immediately in advance of and in line with the bristles projecting through the opening therein, said teeth being adapted to form furrows open 55 to permit the V-shaped tips of the bristle tufts to reach the scalp during the rotation of the rotary brush, and a relatively long tooth of V-shape cross section mounted on the bottom of the casing along each side of the opening therein, said latter teeth along with the former teeth being adapted to transmit the vibrations from the compartment to the scalp over a relatively large area thereof.

and to retain the furrows open to permit the bristle tufts to reach the scalp during the rotation of the rotary brush.

6. An electric hair brush comprising a casing having an opening in the bottom thereof, a compartment formed in the casing over said opening, a brush removably mounted in the casing having bristle tufts extending into the compartment, a rotary brush mounted in the compartment, said brush having two diametrically opposed sets of bristle tufts adapted to pass through the bristle tufts of the first brush and to project through the opening as the rotary brush rotates, each bristle tuft being V-shaped at its outer end, means in the casing for rotating the latter brush, a plurality of longitudinally extending, elongated teeth of V-shape cross section mounted on the bottom of the casing immediately in advance of and in line with the bristles projecting through the opening therein, the rearward ends of the teeth extending beneath part of the end of the opening, said teeth being adapted to form furrows in the hair and to retain the furrows open to permit the V-shaped ends of the bristle tufts to reach the scalp during the rotation of the rotary brush, and additional teeth spaced apart greater than the width of the rotary brush mounted on and extending substantially the entire length of the bottom of the casing.

7. An electric hair brush comprising a casing having an opening in the bottom thereof, a compartment formed in the casing over said opening, a brush removably mounted in the casing having bristle tufts extending into the compartment, a rotary brush mounted in the compartment, said brush having two diametrically opposed sets of bristle tufts adapted to pass through the bristle tufts of the first brush and to project through the opening as the rotary brush rotates, each bristle tuft being V-shaped at its outer end, means in the casing for rotating the latter brush, means associated with the rotary brush for creating vibrations in the compartment, a plurality of longitudinally extending, elongated teeth of V-shape cross section mounted on the bottom of the casing immediately in advance of and in line with the bristles projecting through the opening therein, said teeth being adapted to form furrows in the hair and to retain the furrows open to permit the V-shaped tips of the bristle tufts to reach the scalp during the rotation of the rotary brush, and a relatively long tooth of V-shape cross section mounted on the bottom of the casing along each side of the opening therein, said latter teeth along with the former teeth being adapted to transmit the vibrations from the compartment to the scalp over a relatively large area thereof.

HANS CARL HALUSS. 60
